BLEEDER OR PURGING APPARATUS FOR
REFRIGERATING SYSTEMSThomas H. Rea, Three Rivers, Mich., assignor to
Armstrong Machine Works, Three Rivers, Mich.,
a corporation of Michigan

Application February 17, 1939, Serial No. 257,027

11 Claims. (Cl. 62—115)

This invention relates to improvements in bleeders or purging apparatus for refrigerating systems.

The main objects of this invention are:

- 5 First, to provide an automatic purging or bleeding apparatus for refrigerating systems which is highly efficient, entirely automatic in its operation, and is not likely to become inoperative in use.
- 10 Second, to provide a purging apparatus which, when once set into operation, requires no manual manipulation.

15 Third, to provide an apparatus having these advantages which may be used as a so-called straight purging unit or may be used as a combined expansion valve and purger unit.

Fourth, to provide an apparatus having these advantages which is very compact and has relatively few movable parts.

20 Objects relating to details and economies of the invention will appear from the description to follow. The invention is defined and pointed out in the claims.

Preferred embodiments of the invention are 25 illustrated in the accompanying drawings, in which:

Fig. 1 represents a refrigerating system mainly in diagrammatic form in which the apparatus of my invention is installed to serve as a combined expansion valve and purger.

30 Fig. 2 is an enlarged fragmentary view mainly in vertical section on line 2—2 of Fig. 4.

Fig. 3 is a fragmentary view partially in vertical section on line 3—3 of Fig. 4.

35 Fig. 4 is a view mainly in horizontal section on line 4—4 of Fig. 2.

Fig. 5 is a view mainly in diagrammatic form showing my improved purging apparatus installed as a straight purging unit or apparatus.

40 In the installation shown in Fig. 1, 1 designates the compressor, 2 a condenser, 3 the evaporating coils, and 4 the surge drum of a refrigerating apparatus in connection with which I have shown my purging apparatus which is designated generally by the numeral 5.

This purging apparatus, in the preferred embodiment illustrated, comprises an inlet chamber 6 to which the supply connection 7 delivers, this supply connection being preferably provided with a valve 8. It will be noted that the supply pipe 7 has a delivery nipple 9 projecting centrally of the inlet chamber and terminating in a valve seat for the non-return check valve 10.

Above this inlet chamber is a separating chamber 11 open at its lower end to the upper end of

the inlet chamber. This chamber 11 is surrounded by a jacket 12 forming a refrigerating chamber 13 surrounding the separating chamber, the wall 14 of the separating chamber being the inner wall of the refrigerating chamber or being common to the separating and refrigerating chambers.

The refrigerating chamber has an inlet connection 15 provided with a port having a downwardly facing valve seat 16, this inlet connection 10 connecting the lower end of the refrigerating chamber with the inlet chamber. The valve 17 carried by the lever 18 is adapted to close this connection 15 when the float 19 is in elevated position.

This float 19 is of the inverted bucket type and has a restricted vent or discharge hole 20 at an elevated point in the top thereof. It will be noted that the float embraces the inlet nipple 9 so that the incoming refrigerant or the refrigerant delivered from the pipe 7 is discharged interiorly of the float. Gaseous refrigerant and/or air at this point will collect at the top of the inverted float while the liquid refrigerant communicates freely with the interior of chamber 6 25 through an opening or openings 191 at the bottom of the float.

The separating chamber has an air discharge connection 21 at the top thereof and is provided with a downwardly facing valve seat 22 with which the valve 23 cooperates. This valve 23 is provided with a float 24, the arm 25 of which is pivoted at 26, the valve being connected thereto at 27 so that when the float is lifted by liquid within the separating chamber it closes the valve, the float acting as a weight to open the valve when the liquid level is below the float actuating point.

A gauge glass 29 is provided, this being connected to the upper end of the separating chamber by the valve connection 30 and to the inlet chamber by the valve connection 31. This gauge glass is a matter of convenience in setting the apparatus into operation and also it enables one to determine the liquid level in the separating chamber.

The refrigerating chamber is provided with a discharge connection 32 which delivers to the evaporating coils, the connection being preferably provided with a valve 33.

The air discharge 21 has a valve 34 and delivers into the atmosphere or into a jar indicated at 35 which is of advantage in inspecting a discharge.

To insure that the refrigerant discharged or

the object entering the separating chamber is brought into contact or into intimate relation to the refrigerated wall 14 thereof I provide a deflector 36 which is arranged so that a relatively narrow passage or opening 37 is provided there-around, as shown in Figs. 2, 3 and 4. This substantially increases the efficiency of the apparatus although it will operate without such feature.

In the installation shown in Fig. 5, the receiver 10 38 is connected to the condenser by the line 39 and to the evaporating coils 3 through the pressure regulating valve 40. The inlet pipe 7 of the purging apparatus is connected to the top of the receiver 38 by the connection 41 having a valve 15 42 therein and to the bottom of the receiver through the connection 43 having the valve 44 therein. This structure is the same as that described.

Referring to the installation shown in Fig. 5, the purger may be set in operation as follows. Assuming it to be empty or undercharged, and with the valves 44, 42, 33 and 34 closed, in this condition, the bucket float 19 will be down or in valve opening position as shown in the drawings 25 and the float 24 will also be down or in valve opening position. The first step is to open the valve 44, reference being had to Fig. 5, allowing the purger to become primed or partially filled with liquid refrigerant. The liquid level inside 30 the purger will fill the apparatus to a point substantially above the normal level and liquid refrigerant will pass through the inlet chamber to the refrigerating chamber, filling this normally to a substantially higher level than the level within the separating chamber, the level 35 in the refrigerating chamber depending upon the condenser pressure as well as the position of valve 33. The reason that the refrigerating chamber level will normally be higher than the separating chamber level is that the refrigerating 40 chamber normally contains less air to begin with than the separating chamber and furthermore there is normally more storage capacity for compressed air in the line to valve 33 in practice than there is in practice in the line to valve 34 45 from the separating chamber. Condenser pressure governs the extent to which the air above the liquid levels is compressed, but the location of valves 33, 34 is a factor in the relative height of the levels in the refrigerating and separating 50 chambers. For example, if valve 33 should be four or five feet from the purger, all of the air that was originally in the refrigerating chamber, as well as some of the air from the inlet chamber, can easily be compressed so that it will be 55 contained in such a length of pipe between the purger and the valve. However, if valve 33 is only a few inches from the purger, there will be less pipe space available for storing the air when it is compressed when liquid refrigerant first 60 enters the unit. The same remarks also apply to the location of valve 34 and the liquid level obtaining in the separating chamber; i. e., it is dependent upon the condenser as well as the location of valve 34.

When the purger is primed or partially filled with liquid, the valve 44 is closed, shutting off the supply of liquid refrigerant and the valve 42 is opened, preferably fully, connecting the purger to the top of receiver 38 and the gaseous 65 refrigerant therein. The discharge valve 33 is then cracked or opened slowly. This will allow the pressure in the refrigerating chamber 13 to drop to suction pressure and cause the liquid refrigerant therein to boil. Additional liquid refrigerant will pass into the refrigerating chamber 70

75 through its inlet connection or port 15 slightly lowering the pressure in inlet chamber 6 and separating chamber 11, which in turn allows refrigerant gas and air from the receiver to enter the inlet chamber and collect in the inverted bucket float 19. This element is thereby caused to float and rise, closing the liquid discharge valve 17, i. e., the inlet valve to the refrigerating chamber. In this condition, the interior of the purger will be at high or condenser pressure, 10 whereas the liquid refrigerant in the refrigerating chamber will be boiling under low or suction pressure. The boiling liquid refrigerant in the refrigerating chamber will thus chill the liquid in the separating chamber to within a few degrees of low pressure or suction temperature. In this condition, the refrigerant gas and air passing through the bucket vent 20 will rise through the liquid in the purger and, striking against the baffle 36, will be diverted against 15 the refrigerated or chilled wall of the separating chamber. Since this gas is under condenser pressure but at a decidedly lower temperature, the refrigerant therein will condense and the non-condensable air component thereof will collect in the top of the separating chamber. As 20 the air collects, increasing the pressure on the liquid refrigerant in the separating chamber, the refrigerant level will be lowered as can be observed through the gauge and the liquid thereby displaced will enter the inverted bucket float, causing it to sink and open the inlet connection or port 15, thus discharging the displaced liquid to the refrigerating chamber 13. When this has 25 happened, refrigerant gas and/or air will again enter the inlet chamber and collect in the inverted bucket float causing it to rise and close port 15.

When a substantial quantity of air has been 30 accumulated in the foregoing manner in the dome or top of the separating chamber 11, the air discharge valve 34 may be opened and with further lowering of the liquid level due to accumulation of compressed air as described above, the ball float 24 drops, opening the air valve and discharging air from the purger through air discharge connection 21 to the atmosphere or into inspection jar 35. The valve 44 is then cracked or opened slowly to allow enough liquid refrigerant from the receiver 38 to reach the purger to maintain the desired liquid level for the refrigerating chamber (in practice indicated by the frost level on the outside of the purger casting or on pipe 32, which is caused by condensation and freezing thereon of moisture from the air. Preferably an amount should be admitted sufficient to keep the refrigerating chamber practically filled with boiling refrigerant). Thereafter, the operation of the purger is continuous and automatic. The gaseous refrigerant is caused to condense when it strikes the cold wall of the separator chamber, freeing the air in the mixture, which collects in the dome and operates the air venting float valve in the manner described. After all the air has been purged from the system, it is not necessary to close any 40 of the valves or remove the unit from the line.

Assuming at the start that the valves 8, 33, and 44 are closed, to place the unit of Fig. 1 in operation as a combination expansion valve and purger, the valve 8 is first opened until the 45 purger is primed with liquid refrigerant as indicated by the liquid level in the gauge glass. The valve 33 is then opened slowly, reducing the pressure in the refrigerating chamber to substantially the same pressure as exists in the evaporator. 50

This reduction in pressure causes the liquid refrigerant to boil and chill the wall 14 separating the refrigerant chamber and the separating chamber. Any refrigerant gas that passes through the vent in the inverted bucket float will be condensed when it strikes the cold wall of the separating chamber, as pointed out above. Air which may be mixed with the refrigerant gas cannot condense, but will accumulate in the separating chamber, depressing the liquid level therein and operating the float controlled air release mechanism. Liquid refrigerant will enter the inlet chamber through connection 7 as fast as it is condensed in the condenser 2. As the liquid refrigerant enters the inverted bucket float due to the above depression of the liquid level, the float loses its buoyancy and sinks, opening valve 15 and discharging the liquid to the refrigerating chamber. As refrigerating liquid is discharged to the refrigerating chamber, more refrigerant gas mixed with the air will enter the inverted bucket float causing the float to rise and close valve 15. This cycle is repeated as frequently as desired to discharge the liquid refrigerant from the condenser to the refrigerant chamber and then directly to the evaporator. In addition to the refrigerant condensed in the regular condenser, all refrigerant gas condensed in the separating chamber will also be discharged through valve 15 to the refrigerant chamber and thence to the evaporator.

My purging apparatus is continuous in operation and when once installed is automatic—that is, no other manipulation of the control valves is required. The amount of gas to be purged may be governed by the size of the venting opening in the bucket and the static head that forces the gas through the venting opening. The size of this venting opening can be readily determined for each type of refrigerant. The amount of gas that should pass through the venting opening should be slightly less than the condensing capacity of the heat exchange surface of the separating chamber. Therefore, it is impossible to feed the purger too much gas, and also, it will work at maximum efficiency because nothing less than the maximum amount of gas can be fed to the purging unit. When used as a combination expansion valve and purger it serves a double function. It should be stated that this application is possible only when all of the liquid refrigerant is carried on the low pressure or evaporator side of the system. The inverted bucket mechanism described discharges the liquid refrigerant to the evaporator just as fast as it is formed in the condenser. Any air that is in the system or that may be introduced into the system due to low suction pressures or while charging the system with additional refrigerant will automatically be vented from the purger without attention on the part of the engineer.

I have illustrated and described a practical embodiment of my invention in two installations. I have not illustrated certain modifications in structure that are possible or their various installing adaptations as it is believed that this disclosure will enable those skilled in the art to embody or adapt my improvements as may be desired.

Having thus described my invention, what I claim as new and desire to secure by Letters Patent, is:

1. In a purging apparatus for refrigerating systems, the combination of an inlet chamber having a refrigerant supply connection at the lower end thereof provided with a return check

valve, a separating chamber above and opening to said inlet chamber and provided with a jacket constituting a refrigerating chamber for said separating chamber, said refrigerating chamber having a discharge connection at the top thereof and being provided with an inlet port opening to said inlet chamber and having a downwardly facing valve seat, an upwardly closing valve coacting with said valve seat, an inverted bucket float having a restricted vent opening in the top thereof arranged in said inlet chamber to embrace said supply connection thereof and operatively associated with said valve, an air discharge port at the top of said separating chamber provided with a downwardly facing valve seat, an upwardly seating valve operatively associated with said air discharge port, and a float in said separating chamber operatively associated with said air valve and acting to close the same when the level of the liquid in the separating chamber is sufficient to sustain the float in valve closing position.

2. In a purging apparatus for refrigerating systems, the combination of an inlet chamber having a refrigerant supply connection, a separating chamber above and opening to said inlet chamber and provided with a jacket constituting a refrigerating chamber for said separating chamber, said refrigerating chamber having a discharge connection and having an inlet connection to said inlet chamber, a valve for said inlet connection, an inverted bucket float operatively associated with said valve and having a restricted vent opening at the top thereof, said bucket float being arranged in said inlet chamber to receive the refrigerant and refrigerant gas delivered thereto, an air discharge valve at the top of said separating chamber, and a float in said separating chamber operatively associated with said air valve and acting to close the same when the level of the liquid in the separating chamber is sufficient to sustain the float in valve closing position.

3. In a purging apparatus for refrigerating systems, the combination of an inlet chamber having a refrigerant supply connection, a separating chamber above and opening to said inlet chamber and provided with a jacket constituting a refrigerating chamber for said separating chamber, said refrigerating chamber having a discharge connection and having an inlet connection to said inlet chamber, a valve for said inlet connection, a float in said inlet chamber operatively associated with said valve, a deflector disposed at the lower end of said separating chamber to deflect the refrigerant passing from the inlet chamber into the separating chamber against the wall of said separating chamber, an air discharge valve at the top of said separating chamber, and a float in said separating chamber operatively associated with said air valve and acting to close the same when the level of the liquid in the separating chamber is sufficient to sustain the float in valve closing position.

4. In a purging apparatus for refrigerating systems, the combination of a separating chamber provided with a jacket constituting a refrigerating chamber for said separating chamber, said refrigerating chamber having a discharge connection and an inlet connection, an air discharge valve at the top of said separating chamber, and a float in said separating chamber operatively associated with said air valve and acting to close the same when the level of the liquid in

- the separating chamber is sufficient to sustain the float in valve closing position.
5. In a purging apparatus, the combination of an inlet chamber having a refrigerant supply connection, a separating chamber in communication with said inlet chamber to receive refrigerant therefrom, a refrigerating chamber for said separating chamber, said refrigerating chamber having a discharge connection and an inlet valve, a vented bucket float disposed to receive the refrigerant delivered to said inlet chamber, said float being operatively connected to said refrigerant chamber inlet valve, an air discharge valve for said separating chamber, and a float in said separating chamber operatively connected with said air valve and acting to close the same when the level of the liquid in the separating chamber is at or above a predetermined level.
6. In a purging apparatus, the combination of an inlet chamber having a refrigerant supply connection, a separating chamber in communication with said inlet chamber to receive refrigerant therefrom, a refrigerating chamber for said separating chamber, said refrigerating chamber having a discharge connection and an inlet valve, a float disposed in said inlet chamber and operatively connected to said refrigerating chamber inlet valve, an air discharge valve for said separating chamber, and a float in said separating chamber operatively connected with said air valve and acting to close the same when the level of the liquid in the separating chamber is at or above a predetermined level.
- 35 7. In a purging apparatus, the combination of an inlet chamber having a supply connection, a separating chamber in communication with said inlet chamber to receive liquid and gas therefrom, cooling means for said separating chamber, a float disposed in said inlet chamber, a liquid discharge valve for said inlet chamber operatively associated with said float to control the discharge of the liquid from said inlet chamber in accordance with the position of said float, an air discharge valve for said separating chamber, and a float in said separating chamber operatively associated with said air discharge valve.
8. In a purging apparatus, a chamber having an opening for admitting a liquid refrigerant and a gaseous refrigerant mixture containing air to the chamber, a float associated with said opening and adapted to collect said gaseous mixture and to be elevated thereby in said liquid, a refrigerating chamber having a portion common to said first named chamber and having a connection to said chamber, and valve means for said connection controlled by said float to admit liquid refrigerant from said first named chamber to said refrigerating chamber when the float is lowered, said refrigerating chamber having a valve controlled discharge line to decrease the pressure in the refrigerating chamber when said line is open and thereby cause liquid refrigerant in the refrigerating chamber to boil and chill said common portion of the refrigerating and first named chambers, said float having provision for slowly freeing said gaseous mixture collected thereby, whereby said mixture arises into contact with and is chilled by said chilled portion, the gaseous refrigerant in the mixture condensing and the air collecting at the top of the first named chamber, resultant increase in air pressure in said first named chamber causing said float to be depressed whereby said
- first named connection is opened for entrance of liquid to said refrigerating chamber.
9. In a purging apparatus, a purging chamber adapted to contain liquid refrigerant and having a connection thereto for admitting a gaseous refrigerant mixture containing air to the chamber, control means associated with said connection and adapted to collect said gaseous mixture admitted therethrough, a refrigerating chamber including a portion in heat transmitting relation to said first named chamber, said refrigerating chamber having an opening communicating with said first named chamber to admit liquid refrigerant thereto from the first named chamber, a valve for said opening controlled by said control means whereby the opening is closed when the control means is elevated, said refrigerating chamber being adapted to have a relatively low pressure created therein to reduce the pressure sufficiently to cause said liquid refrigerant in the refrigerating chamber to boil and chill said portion, said control means having a vent therein for slowly venting said gaseous mixture into the first named chamber, said mixture arising above the liquid in said first named chamber and contacting said chilled portion whereby the gaseous refrigerant condenses and air in the mixture collects at the top of said chamber, increase in air pressure in said chamber causing the liquid refrigerant to actuate said control means whereby said opening is exposed for entrance of liquid refrigerant and condensate to said refrigerating chamber, and means for removing air from said first named chamber.
10. In a purging apparatus, a purging chamber adapted to contain liquid refrigerant and having a connection thereto for admitting a gaseous refrigerant mixture containing air to the chamber, a hollow float associated with said connection and adapted to collect said gaseous mixture admitted therethrough and to be elevated thereby in liquid refrigerant contained in the chamber, a refrigerating chamber having a wall common to said first named chamber and having an opening communicating with said first named chamber to admit liquid refrigerant thereto from the first named chamber, a valve for said opening controlled by said float whereby the opening is closed when the float is elevated, said refrigerating chamber being adapted to have a relatively low pressure created therein to reduce the pressure in the refrigerating chamber sufficiently to cause said liquid refrigerant to boil and chill said wall, said float having a vent therein for slowly venting said gaseous mixture from said float into the first named chamber, said mixture arising above the liquid in said first named chamber and contacting said chilled wall whereby the gaseous refrigerant condenses and air in the mixture collects at the top of said chamber, increase in air pressure in said chamber causing the liquid refrigerant to enter said float whereby the latter sinks and said valve is actuated to expose said opening for entrance of liquid refrigerant and condensate to said refrigerating chamber, and means for removing air from said chamber.
11. In a purging apparatus, the combination of a chamber having an opening for the admission of a gaseous refrigerant mixture containing air thereto, said chamber being also adapted to receive a quantity of liquid refrigerant, a hollow vented float member disposed in the liquid in said chamber adjacent said opening, said member being adapted to collect said gaseous mix-

ture admitted to the chamber and to be elevated thereby in said liquid refrigerant, means for chilling at least a portion of the wall of said chamber, the vent in said float member slowly venting said gaseous mixture from the float member, said vented mixture arising above the liquid in said chamber and contacting said chilled portion whereby the gaseous refrigerant

condenses and air in the mixture collects at the top of the chamber to thereby depress the level of the liquid, said chamber having an air discharge opening, and means coating with said last named opening to vent the collected air from the chamber. 5

THOMAS H. REA.
